COMBINED SCOURING PAD AND SPONGE

Annette T. Stoker, 311 N. 7th St., Burbank, Calif.

Filed Feb. 21, 1963, Ser. No. 73,668

Term of patent 14 years

(Cl. D9—2)

FIG. 1 is a top perspective view of a combined scouring pad and sponge, showing my new design.

FIG. 2 is a top plan view thereof; and

FIG. 3 is a side elevational view thereof.

It is understood that the partial net pattern as illustrated is continuous throughout the scouring pad element.

I claim:

The ornamental design for a combined scouring pad and sponge, as shown and described.
